UNITED STATES PATENT OFFICE.

JOHN MERRY, OF BROOKLYN, NEW YORK, ASSIGNOR TO THE BIGELOW CARPET COMPANY, OF CLINTON, MASSACHUSETTS.

DESIGN FOR A CARPET.

SPECIFICATION forming part of Design No. 14,767, dated February 19, 1884.

Application filed January 16, 1884. Term of patent 3½ years.

To all whom it may concern:

Be it known that I, JOHN MERRY, a resident of Brooklyn, in the county of Kings and State of New York, have invented and produced a new and original Design for a Carpet, of which the following is a full description, in connection with the accompanying photograph, which represents a face view of my new design for a carpet.

This invention relates to a new ornamentation of the face of a carpet, oil-cloth, or analogous fabric.

In the accompanying photograph are shown two principal bands, A and B, into which the face of the carpet is divided. The ornamenta-

tion of the band B consists of the novel grouping of the different figures indicated in the photograph, of which *a* is a cluster of flowers and leaves, from which extend various branches, and *b* is a shrub bearing flowers *d*. *e* is a zigzag band interposed between the bands A and B.

I claim—

The design for a carpet, the same consisting of the figures A, B, *a*, *b*, *d*, and *e*, substantially as shown.

JOHN MERRY.
